[57] CLAIM

The ornamental design for a combination axe and basher-adz device, as shown as described.

DESCRIPTION

FIG. 1 is a perspective view of a combination axe and basher-adz device showing my new design.

FIG. 2 is a side elevational view of a combination axe and bashing-adz device showing my new design.

FIG. 3 is top plan view thereof.

FIG. 4 is a bottom plan view thereof.

FIG. 5 is a right-end elevational view thereof.

FIG. 6 is a left-end elevational view thereof.
